UNITED STATES PATENT OFFICE.

JOHN SEITZ, OF HAYSVILLE, INDIANA.

MOLE-TRAP.

SPECIFICATION forming part of Letters Patent No. 549,977, dated November 19, 1895.

Application filed March 23, 1895. Serial No. 542,956. (No model.)

To all whom it may concern:

Be it known that I, JOHN SEITZ, a citizen of the United States, residing at Haysville, in the county of Dubois and State of Indiana, have 5 invented a new and useful Mole-Trap, of which the following is a specification.

This invention relates to an improvement in mole-traps; and the object of the invention is to provide a simple and inexpensive construction of trap which shall possess the requisite strength and durability, which shall be capable of catching a mole in whichever direction it travels, and shall be thoroughly efficient in practice.

15 To this end the invention consists in a trap comprising a suitable frame, a pair of oppositely-disposed slings or chokers, a pair of spring-arms for operating said slings, and a pair of triggers adapted to lie in the path or 20 burrow in which the mole travels and to be operated by the mole for releasing the spring-arms and causing the latter to exert their tension for drawing the slings through and between suitable guides, thereby causing said 25 slings to grasp the mole and choke it or prevent its escape.

The invention also consists in certain features and details of construction and arrangement of parts hereinafter fully described, illustrated in the drawings, and 30 pointed out in the claims.

In the accompanying drawings, Figure 1 is a perspective view of a mole-trap constructed in accordance with my improvements. Fig. 35 2 is a side elevation of the same. Fig. 3 is an end view thereof.

Similar numerals of reference indicate corresponding parts in the several figures of the drawings.

40 Referring to the drawings, 11 indicate two longitudinal and parallel bars, which are connected by a centrally-arranged transverse bar 2, said bars 1 and 2 being formed of wood or any suitable or preferred material and constituting the main supporting-frame of my 45 improved trap. A centrally-arranged vertical post or standard 3 is secured upon the transverse bar 2, and is provided at its upper end with a notch or slot 4 for the reception of a pair 50 of spring-arms 5, as shown. The spring-arms 5 are preferably formed from a single piece of spring-wire, having several central coils 6

for imparting increased elasticity thereto, and with a downward extension or eye 7, lying in the slot 4 in the upper end of the standard 3, 55 being secured in place by means of a bolt and nut 8. A perforated metallic U-shaped cap 9 is fitted over the upper end of the standard or post 3, being perforated to receive the bolt 8, and also having a central opening for the 60 passage of the downwardly-extending eye of the spring-armed device, the object of said cap being to prevent the upper end of the standard 3 from splitting and also to afford a firmer support for the spring-arms. 65

The spring-arms 5 at their outer extremities are provided with eyes 10, from which small pendent chains or cords 11 extend downwardly to about the horizontal plane of the frame 1, where they are attached to and support each a circular sling or choker in the form of a wire loop 12, lying between and adapted to move vertically within the space between two parallel pieces of wire 13, secured to pins 13^a, projecting laterally from 70 the ends of the frame-bars 1. A centrally-arranged connecting wire or cord 13^b prevents the sling from escaping from between the wires 13. The slings or wire loops 12 may, of course, be of any preferred form or size, 75 and the springs 5 for operating said slings may be made from spring-wire of any desired gage having the necessary spring power. 80

A longitudinally-extending bar or support 14, passing through a mortise 15 in the vertical standard 3, projects laterally upon either side of said standard and is bifurcated and perforated at either end to receive the vertically-extending arms 16 of a pair of triggers or shovels 17, projecting downwardly beneath 90 the frame-bars 1 and in longitudinal line with the slings or loops 12 when the trap is set. At or near their upper ends the arms 16 are notched, as shown at 18, to engage the outer opposite extremities of two catches or plates 95 19, which are supported at their inner ends beneath stationary blocks or cleats 20. From convenient points intermediate the ends of the catches 19 chains or cords 21 extend upwardly to and connect with the springs 5 for 100 holding the latter down and allowing the slings or loops to occupy a position beneath the frame-bars 1, as indicated in Fig. 2.

From the foregoing description the opera-

tion will be readily understood. When the trap is set, as shown in Fig. 2, the base-frame is placed upon the ground just over the burrow made by the mole and pressed downward 5 until the triggers 17 lie in said burrow, and the slings or loops 12 are then adjusted so that they will surround the burrow in such a way that the mole will pass through one or the other, according to the direction in which 10 it is traveling. A sufficient amount of earth is now banked up over the base-frame to hold the same firmly anchored. As the mole advances through the burrow which it had formerly made it comes in contact with the shovel 15 or trigger 17, rocking the lower end thereof inward toward the center of the trap, throwing the upper end of its arm 16 outward, releasing the catch 19, and allowing the spring-arm 5 to act, by means of which the sling or 20 loop 12 is drawn quickly upward with the full force of the spring, thereby grasping the mole between the lower portion of the loop or sling and the parallel guiding-wires 13 and preventing its escape or choking it in a manner 25 that will be readily understood.

Various changes in the form, proportion, and the minor details of construction may be resorted to without departing from the principle or sacrificing any of the advantages of 30 this invention.

Having thus described the invention, what is claimed as new, and desired to be secured by Letters Patent, is—

1. In a mole trap, a supporting base or 35 frame comprising a pair of longitudinal bars spaced apart and rigidly connected by a central transverse bar, and a pair of parallel wires extending across and connecting the projecting ends of said longitudinal bars, in 40 combination with an upright or post secured to said transverse bar, a bifurcated bracket or support extending longitudinally from said post, a trigger pivoted to said bracket, a spring arm projecting longitudinally from 45 and connected with the upper end of said post, a loop or sling suspended from the free end of said spring arm, a horizontally disposed catch plate engaging at one end be-

neath a stop on the post or upright and also engaging at its opposite end the upper end of 50 the pivoted trigger, and a flexible connection between said catch plate and spring arm, all arranged substantially as and for the purpose specified.

2. In a mole trap, a suitable base or frame, 55 and a vertical post or standard mounted thereon, in combination with a spring arm mounted in said post or standard, a vertically movable sling or loop connected with said spring arm and actuated thereby, a pair of parallel wires 60 or guides attached to the base or supporting frame for directing the movements of the sling or loop, a wire extending around and connecting said parallel wire or guides and forming a stop for limiting the upward movement 65 of said sling or loop, a trigger pivotally supported upon one side of the vertical post or standard and projecting at its lower end beneath the base or supporting frame, a horizontally disposed catch for engaging the upper end of the trigger, and a chain or cord interposed between said catch and the spring arm, all arranged and adapted to operate, 70 substantially as set forth.

3. The herein described mole trap, the same 75 comprising a pair of longitudinal bars spaced apart and connected by a central transverse bar, a vertical post or standard arising from said transverse bar and provided in its upper end with a downwardly extending slot or 80 notch, a perforated metal cap secured to the upper end of said post or standard, a spring arm passing through said cap and into the post, parallel guiding wires connecting the projecting ends of the longitudinal bars, a 85 loop or sling suspended from the spring arm, and means for setting and releasing said sling, substantially as and for the purpose described.

In testimony that I claim the foregoing as 90 my own I have hereto affixed my signature in the presence of two witnesses.

JOHN SEITZ.
